United States Patent Office

Des. 185,385
Patented June 2, 1959

185,385

CALCULATING-LISTING MACHINE

Jiri M. Nessel, Los Angeles, Calif., assignor to Clary Corporation, San Gabriel, Calif., a corporation of California

Application March 7, 1958, Serial No. 49,938

Term of patent 14 years

(Cl. D64—11)

Des. 185,385

PAGE 2

FIG. 3

Fig. 1 is a perspective view of a calculating-listing machine showing my new design.

Fig. 2 is a side view, the opposite side thereto being substantially similar in appearance; and

Fig. 3 is a plan view thereof.

The essential features of my design reside in the parts shown in full lines.

I claim:

The ornamental design for a calculating-listing machine, substantially as shown and described.
